UNITED STATES PATENT OFFICE.

ZISSO DEMETRIO BEBIS, OF PARIS, FRANCE.

SHEET OF PAPER FOR COMMERCIAL CORRESPONDENCE.

1,278,424.

Specification of Letters Patent. Patented Sept. 10, 1918.

Application filed April 21, 1916. Serial No. 92,756.

To all whom it may concern:

Be it known that I, ZISSO DEMETRIO BEBIS, a subject of the King of Greece, resident of Paris, France, and whose post-office address 5 is 8 Cité Rougemont, Paris 9e, France, have invented certain new and useful Improvements in a Sheet of Paper for Commercial Correspondence, of which the following is a specification.

10 My invention relates to a novel form of writing paper for postal correspondence.

The object of my invention is to provide a sheet of paper which permits both sides being written upon, either by hand or by a 15 type-writer, while the address, by folding the sheet, will be kept on a visible part of same and the writing entirely hidden.

A further object of my invention is to provide means whereby said sheet of paper 20 may be opened after sealing without spoiling either the sheet or the writing.

One form of my invention is represented by way of example in the annexed drawing, wherein:—

25 Figure 1 shows the form of the sheet before folding.

Fig. 2 represents a side edge view of the sheet.

Fig. 3 represents a similar view of the 30 sheet in the first step of its folding.

Fig. 4 represents the second step of the folding.

Fig. 5 is a front view of the sheet before finally folding and

35 Fig. 6 shows the sheet in its finally closed position.

Like reference letters designate like parts throughout the several figures.

The sheet of paper consists of a blank 40 piece divided into three rectangular folds or sections: *a*—*b*— and *c*. The outer edges of the fold *a*— are surrounded by a gummed flap *d*— and said flap is detachable from said fold *a*— by means of perforations.

45 The sections *b* and *c* are adapted to be folded along the line *EE'*. To the outer edge of the lower fold *c*— is attached a gummed flap *e*—, provided with a row of perforations *g* and a similar row of perforations *f*— 50 is in the fold *c* adjacent the flap *e*.

On using the sheet for correspondence purposes the address may be written either on the right hand or the left hand half portion of fold *a*—.

The contents of the letter may be written 55 on the whole back surface of the sheet and also the front face of folds *b*— and *c*—.

To close the letter proceed as follows:

Turn fold *a*— along the line *AA'* in the direction of the arrow *m* (Fig. 2). 60

Turn the coincident folds *a*—*b* along the line *EE'* as indicated by arrow *n*— (Fig. 3) down on fold *c*. Turn flap *e*— along the line *DD'* as indicated by arrow *r*, (Fig. 4). By these steps the blank has that form 65 shown in Fig. 5.

Fold the left hand portion of Fig. 5 on line *NR* down on right-hand portion, after the flap *e*— has been fixed by its gummed side on the sheet. Moisten the gummed flaps 70 *d*— and secure the two coincident half portions of section *a* together to arrive at the form shown on a larger scale in Fig. 6.

When the sheet has thus been folded the 75 perforated lines *d* *f* and *g* overlie in such a manner that the letter may be opened by breaking the paper along the lines of these perforations; *i. e.* along the perforated lines shown in Fig. 6.

Having now particularly described the 80 nature of my invention what I claim is:

A sheet of letter paper and an integral inclosure therefor comprising a blank sheet having two parallel dividing lines forming the sheet into two terminal sections and an intermediate section all of substantially equal dimensions, gummed flaps along the entire lengths of the three marginal edges of one of said terminal sections and lines of 85 perforations where said flaps join said terminal section, a gummed flap along the end edge of the other terminal section and having its end portions projecting beyond the side edges of the adjacent terminal section, 90 said flap and said adjacent terminal section 95 having parallel lines of perforations and the perforated line of the flap being turned at right angles where said flap projects at the sides of the sheet, said terminal sections adapted to be folded against opposite sides 100

of the intermediate section and then the whole sheet folded upon itself at right angles to the lines of said first named foldings, the gummed flaps adapted to secure the parts thus folded along the marginal edges thereof, and said lines of perforations of the folded sections adapted to overlie each other whereby the seal of the letter may be broken.

by tearing along the perforated lines, substantially as set forth.

In testimony whereof I have affixed my signature in presence of two witnesses.

ZISSO DEMETRIO BEBIS.

Witnesses:

TASSO P. CASOTTI,
CHAS. P. PRESSLY.
